R. P. BAUGH.
WASHING MACHINE.

P No. 439,266.

Patented Oct. 28, 1890.

UNITED STATES PATENT OFFICE.

REUBEN P. BAUGH, OF MIDLAND, TEXAS.

WASHING-MACHINE.

SPECIFICATION forming part of Letters Patent No. 439,266, dated October 28, 1890.

Application filed November 26, 1889. Serial No. 331,727. (Model.)

To all whom it may concern:

Be it known that I, REUBEN P. BAUGH, a citizen of the United States, residing at Midland, in the county of Midland and State of 5 Texas, have invented certain new and useful Improvements in Washing-Machines, of which the following is a specification.

The object of the present invention is to provide a washing-machine which will rapidly 10 wash clothes of coarse or fine texture without injury thereto. This object I accomplish by my improved washing-machine, which consists, essentially, of a cylindrical body, a flexible and adjustable wash-board in the lower 15 half thereof, and a corrugated drum rotating in the body above the wash-board, as well as of the adjunctive and specific details of construction incident thereto, which assist in carrying out the object in view, and certain auxiliaries which tend to enhance the value of 20 the completed machine, all as hereinafter more fully described.

In the accompanying drawings, Figure 1 is a perspective view of my improved washing-machine closed. Fig. 2 is a plan view of the 25 same when open. Fig. 3 is a central longitudinal section of Fig. 2 on the line 3-3. Fig. 4 is a perspective view of the wash-board detached. Fig. 5 is an end view of the supplemental roller as used in connection with the 30 machine, the latter being shown in dotted lines. Fig. 6 is a perspective detail of the discharge-opening in the body and the button for closing it.

Referring by letter to the said drawings, B 35 designates the body of my improved washing-machine, which is preferable approximately cylindrical in shape with a horizontal shelf b at one side, and this body is provided horizontally on about the line of the shelf with 40 hinges, as at b', so that it can be opened, as shown in Fig. 2. The body is supported by legs L and the upper half by a supplemental and removable leg l when in open position.

Journaled in disks d on the ends of the lower 45 half of the body is a shaft carrying a drum D, having a corrugated outer surface or periphery, and one end of the shaft is cranked, as shown, whereby the said drum may be rotated within the body. At one edge of the 50 lower half a wringer W is removably connected therewith, the crank of this wringer

extending beyond the end of the body, as shown. The wringer proper forms no part of the present invention; but by locating it near 55 the hinges b', connecting the two portions of the body, the clothes after having been washed in the lower portion can be passed through the wringer over and into the upper portion, which is inverted, as shown in Fig. 2. 60

The wash-board O consists of a number of perforated longitudinal strips connected on the outer faces by flexible metallic bands n near their ends, and also by a similar central band N, which extends beyond one end of the 65 wash-board, and is provided with a hook i in its free end, as shown. The other end strip of the wash-board is cut away on its inner edge at its ends, leaving trunnions o, which are journaled in C-shaped sockets secured 70 to or formed upon the inner face of the ends of the body, as shown at S. A friction-roller R is mounted on the shelf b, and over this roller the band N passes, its hook engaging an eye I in a lever L, which is pivoted at its 75 lower end to a semicircular plate M, having teeth m of ratchet shape on its outer edge. A spring-operated pawl P is carried by said lever and engages said teeth m, when the lever is turned outwardly, and the upper end of 80 the pawl is hooked, as at p, whereby it may be retracted to disengage it from the wheel.

The letter U designates a supplemental roller, which is journaled in a frame-work F, having handle H and hooks h at the outer 85 ends of its side arms. These hooks are adapted to be engaged with eyes f, secured upon the ends of the body, all as shown in Fig. 5.

The operation of my improved washing-machine is as follows: The body is opened, 90 the wash-board put in place, and hot water and soap put with the clothes into the body upon the upper face of the wash-board. The latter is then adjusted by the lever L so that it shall stand relatively as close to or as far 95 from the drum D as desired, whereby a greater or less degree of pressure and force of the rubbing portion can be applied to the clothes according as they are of coarse or fine texture and in large or small bulk. The top is then 100 preferably closed to retain the steam and heat, and the drum D rotated or oscillated by its handle. The top is then opened and may be filled with blue-water, and the clothes are

passed through the wringer W and into such water, from which they may be again wrung out and hung out to dry.

It often occurs that it is desirable to wash 5 bed-quilts, counterpanes, and other large and bulky articles which will hardly pass beneath the drum even if the wash-board were dropped to its lowest point, and to provide for this I have constructed the supplemental 10 roller U shown in Fig. 5. The hooks h are passed through the eyes f, and the frame F is then turned so that the roller will be brought down upon about the center of the drum. The bulky article being washed is 15 then wet and soaped, after which it is passed between the roller and the drum, and the latter is rotated to move it along from one end to the other. Meanwhile the handle H is pressed upon to impart the desired pressure to the 20 article, and the free end of the latter on the feeding side of the roller of the drum can be held, if desired, so that the ribs on the drum will rub it beneath the roller. After having been washed the article is passed through the 25 wringer W, blued, wrung out again, and hung out to dry.

At a suitable point in the bottom of the body is formed a hole which is surrounded on the outside of the body by a ring or washer 30 G, and a button T, having its face provided or coated with leather, rubber, or other soft material, is pivoted at t, so as to swing across the outer face of the washer G and close the hole. Stops g are provided at either side of 35 the button to limit its movement.

At one end of the body a shelf E is connected by a hinge e on its upper side to one of the legs or frame-work L of the body, so that when the shelf is turned down its edge 40 will strike against the legs and frame-work and retain the shelf in a horizontal position. This shelf may be useful for supporting a clothes-basket, soap-dish, bluing-bottles, and for other purposes.

On the outer face of the upper half of the 45 body is provided a socket Q, within which the upper end of the supplemental leg l may be removably fitted, if desired. The upper half of the body is preferably a segment of a 50 slightly-smaller circle than the lower half, whereby the outer edge of the former fits closely by the inner edge of the shelf b when the parts are closed, as shown in Fig. 1.

The drum D may be made hollow and its 55 periphery composed of a number of strips, each having several corrugations or ribs formed in and upon its outer face.

Although I have not so illustrated and claimed it, the body B may be provided with 60 one or more partitions parallel with its ends and the drum D, and even the wash-board O, if desired, may be made in sections, each sec-

tion fitting one apartment, but the shaft of the drum extending through all the partitions; but I prefer usually to construct my washing- 65 machine as above described, as this dividing up of its length would make it too large and unwieldy to be run by hand, and would necessitate the use of steam-power, and perhaps require the attention of several operators. This 70 construction of the machine, however, might be of use in steam-laundries or other places doing a large business.

It will be understood that these auxiliaries described above are not essential to the successful operation of this device; but I prefer to employ them if possible in order to render the machine finished in every detail and a perfect piece of mechanism when it is sold to the user. 80

What I claim is—

1. In a washing-machine, the combination, with a drum journaled in bearings in the body of the machine, of a flexible wash-board pivotally connected at one end to said body at 85 one side of the drum, a band leading from the other end of said wash-board, a toothed plate secured to the body, a lever pivoted to said plate and having a spring-operated catch or pawl engaging said teeth, and connections 90 between said lever and the free end of the band, as and for the purpose set forth.

2. The combination, with the semi-cylindrical receptacle having a shelf along one edge and a drum journaled in bearings in the ends 95 thereof, of a flexible wash-board pivotally connected within and to one side of the body and passing beneath the drum, a flexible band connected to the free edge of the wash-board, a pulley mounted on said shelf and over 100 which the band passes, a semicircular plate upon the outer face of the body opposite said pulley, provided with teeth on its edge, a lever pivoted to said plate and connected to the free end of said band, and a spring-pawl carried by the lever and engaging said teeth, 105 substantially as described.

3. The semicircular plate M, secured to the body B and having downwardly-facing ratchet-teeth m in its edge, in combination with the lever L, pivoted to said plate, the pawl P, sliding alongside said lever and its upper end p bent outwardly, a spring for throwing said pawl into engagement with said teeth, an eye I near the outer end of the lever, a flexible wash-board, a flexible band leading therefrom, and a hook i in the free end of said band adapted to engage said eye in the lever, all as and for the purpose described. 115
